(57) CLAIM

The ornamental design for a light bulb removal and installation tool, as shown and described.

DESCRIPTION

FIG. 1 is a left side of the present invention, and
FIG. 2 is a right side view of the present invention, and
FIG. 3 is a bottom view of the present invention; and
FIG. 4 is a top side view of the present invention; and,
FIG. 5 is a perspective view of the present invention, wherein the dotted lines illustrate use and environment forming no part of the claimed design.
